(57) **CLAIM**

What is claimed is the ornamental design for a sanitary leakage preventive fin, as shown and described.

DESCRIPTION

FIG. 1 is a front view of a sanitary leakage preventive fin showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top left perspective view thereof;

FIG. 8 is a top left side perspective view thereof shown in a closed state;

FIG. 9 is a top left side perspective view thereof shown in a semi-open state; and,

FIG. 10 is a top view thereof shown in an open state.

The broken lines shown in FIGS. 8-10 illustrate environment that form no part of the claimed design.
